UNITED STATES PATENT OFFICE.

ISAAC N. WISE, OF YAZOO CITY, MISSISSIPPI.

SELF-LUBRICATING SPRING.

1,325,431.

Specification of Letters Patent. Patented Dec. 16, 1919.

Application filed February 11, 1919. Serial No. 276,288.

To all whom it may concern:

Be it known that I, ISAAC N. WISE, a citizen of the United States, residing at Yazoo City, in the county of Yazoo and State of 5 Mississippi, have invented new and useful Improvements in Self-Lubricating Springs, of which the following is a specification.

This invention relates to certain novel and useful improvements in self lubricating 10 springs and has particular application to a self lubricating leaf spring structure for vehicles.

In carrying out the present invention it is my purpose to provide a self lubricating 15 leaf spring structure wherein the individual leaves will be so formed that a supply of oil or other lubricant may traverse the spring structure between the individual leaves thereof thereby enabling the structure to be 20 thoroughly and efficiently lubricated at all times.

Another object of my invention is the provision of a self lubricating structure of the 25 class described which will embrace the desired features of simplicity, efficiency and durability, which may be manufactured at a small cost and which will be self lubricating under all conditions.

With the above recited objects in view and 30 others of a similar nature, the invention resides in the construction, combination and arrangement of parts, set forth in and falling within the scope of the appended claim.

In the accompanying drawing:—

35 Figure 1 is a view in side elevation of the upper section of a leaf spring structure constructed in accordance with my present invention.

Fig. 2 is a bottom plan view of one of the 40 leaves.

Fig. 3 is a longitudinal sectional view through the spring structure.

In the present instance, I have shown my invention as applied to the upper section of 45 a leaf spring structure and in this connection it will be understood that my invention is equally applicable to the lower section of the spring structure and is, in fact, capable of use in any type of leaf spring structure.

50 Referring now to the drawing in detail, the numeral 1 designates the individual leaves of the upper section of a leaf spring structure. As usual, these leaves are placed

one upon the other, in face to face contact and secured together by means of clips 2 55 that hold the leaves against accidental relative movement laterally. In accordance with my invention the lower side of each leaf 1 of the spring is formed with a longitudinal channel 3 which terminates short of 60 the respective ends of the leaf. Each leaf is also formed with openings 4 suitably spaced apart and opening onto the lower side of the next adjacent leaf above the particular leaf. The openings 4 in the top leaf of the 65 spring carry oil cups 5 which may be threaded or otherwise secured in the respective openings. The bottom leaf of the spring structure is not formed with openings 4 but presents an unbroken surface thereby enabling the lubricant to be retained in the upper surface in the bottom leaf within the groove or channel 3 of the next adjacent leaf.

From the foregoing description taken in 75 connection with the accompanying drawing, it will be seen that I have provided a self lubricating spring structure wherein the individual leaves of the spring will be thoroughly and efficiently lubricated so that 80 when excessive strain is placed thereon the leaves may have the necessary relative movement to one another to take up the shock or rebound. At the same time, my improved self lubricating spring structure will outlive 85 the usual spring structure for the reason that the individual leaves are thoroughly lubricated under all conditions thereby preventing rusting of the leaves and consequent deterioration thereof. 90

I claim:—

A self lubricating spring structure comprising a plurality of superposed leaves, the bottom leaf being continuous and each of the remaining leaves being provided in its 95 underside with a single central longitudinal groove terminating short of the ends of the leaf, each leaf being further provided in the groove with a series of circular holes, the topmost leaf having only two holes, the holes 100 in the successive leaves being in staggered relation, and oil cups threaded into the holes in the topmost leaf.

In testimony whereof I affix my signature.

ISAAC N. WISE,
